(57) **CLAIM**

The ornamental design for a diffuser for modifying light distribution, as shown and described.

DESCRIPTION

FIG. 1 is a top perspective view of a diffuser for modifying light distribution showing my new design;

FIG. 2 is a bottom perspective view thereof;

FIG. 3 is a top plan view thereof;

FIG. 4 is a bottom plan view thereof; and,

FIG. 5 is a front elevational view thereof, the rear and sides adjacent being identical in appearance.

The broken line disclosure represents portions of the diffuser which form no part of the claimed design.
